UNITED STATES PATENT OFFICE.

MILLER REESE HUTCHISON, OF DEAL BEACH, NEW JERSEY, ASSIGNOR TO LOVELL-
McCONNELL MANUFACTURING COMPANY, A CORPORATION OF DELAWARE.

ALARM AND SIGNALING DEVICE.

1,173,577.

Specification of Letters Patent. Patented Feb. 29, 1916.

Application filed December 29, 1910. Serial No. 599,926.

To all whom it may concern:

Be it known that I, MILLER REESE HUTCHISON, a citizen of the United States, and resident of Deal Beach, in the county of Monmouth and State of New Jersey, have invented certain new and useful Improvements in Alarms and Signaling Devices, of which the following is a specification.

This invention relates to motor driven or power signals adapted for use on automobiles, launches, factories and wherever a signal of carrying power and insistent quality is desirable.

The signal constituting the present invention comprises a diaphragm, with which is typically associated a projector, resonator or amplifier, a toothed rotor for setting up diaphragm vibrations, a flexible shaft carrying the rotor and adapted for resilient lateral movement to and from the diaphragm, a motor or power means for rotating the shaft, and a solid cylindrical bearing at the end of the flexible shaft connecting with the motor. Such a bearing makes it possible to successfully operate by an electric motor, a resiliently mounted rotor, since it mechanically insulates the armature and commutator from the bodily movements and vibrations of the flexible shaft, which would otherwise be communicated to the armature shaft and interfere with the proper operation of the motor.

In the simplest embodiments of the invention the elasticity of the flexible shaft is inherent in the shaft itself. Here the cylindrical bearing has the further function of solidly holding a length of the flexible shaft. Preferably the shaft is solidly held at both end portions, in rigid journals preferably of greater diameter than the flexible portions so that these portions of the shaft remain in alinement notwithstanding the bodily vibrations of the remainder of the shaft. Preferably, also, the rotor is rigidly secured to the shaft, as at the center thereof, by a connection, preferably a rigid sleeve, which during operation maintains an intermediate length of the shaft in parallelism with the solidly held end portions. These

several connections not only afford a durable and wear-resisting construction, but also greatly aid in the elastic action of the shaft. In the typical case of the shaft being solidly held at the ends and having a central portion held in parallelism therewith, two outward curves and two reverse curves are formed in the shaft under running conditions, instead of a single outward or bowed curve which would result if the shaft were permitted to spring out of alinement at its ends and were connected to the rotor in such manner as to permit an uninterrupted bend of the center. If one only of these flexure-preventing connections are employed, compound curvature is still obtained though the number of bends is correspondingly reduced.

It has been proposed to make a campaign rattle with the diaphragm relatively stiff and the shaft relatively flexible so that the bodily movement of the rotor is great as compared with the movement of the diaphragm or anvil and the rotor is practically a cam operated spring tapper. The shaft being more flexible than the diaphragm is cammed away from the anvil by the rotation of the rotor in contact therewith; when one tooth slips off, the shaft springs back and the next tooth delivers a sharp blow on the anvil of the diaphragm. The shaft is again forced away and the hammering continues as long as the rotor turns.

In my improved signal the parts are so constructed and related that the hammering action is minimized or practically eliminated. The shaft is rotated at high speed, and the flexible shaft may be comparatively long, and the rotor may be comparatively heavy, whereby the natural period of the shaft is suppressed under working conditions and the shaft takes on a set or bow at maximum speed which lasts as long as the speed is maintained. In this construction and particularly if the rotor be provided with cam faces of low pitch there will be little vibratory movement of the shaft at each individual cam contact, the cam will assume a position of flexure normally constant so long as the speed is maintained, and

vibration of the diaphragm will be mainly due to the successive cam surfaces camming the diaphragm outward, the action being more like that of a true cam with a normally unyielding but automatically self-adjusting axis. In this case the rotor is initially forced outward by the diaphragm until it acquires the set or normally constant running position, after which the rotor axis remains practically fixed so long as the speed is maintained. Thus, a sustained note may be obtained by the resulting bodily vibrations of the diaphragm, which is quite different from that resulting from the vibratory tapping previously referred to. Between these limits of maximum shaft vibration and maximum diaphragm vibration in response to the camming contacts, there is a large range of specific constructions in which the diaphragm-camming action predominates in varying degrees, or in which there is about as much of one as the other.

In the drawings illustrating some of the possible embodiments of the invention: Figure 1 is a view of a signal, partly in vertical section and partly in elevation and with the resonator partly broken away, adapted to produce a sustained note with minimum hammering effect; Fig. 2 is a semi-diagrammatic, exaggerated view illustrating the curvature of the flexible shaft under running conditions; Fig. 3 is a sectional plan showing a rotor and anvil which might be employed. Fig. 4 is a view similar to Fig. 1, showing another embodiment of the signal; Figs. 5 and 6 are views similar to Fig. 1, showing forms of signal in which elastic means are associated with the flexible shaft; and Fig. 7 is a sectional plan of the signal shown in Fig. 6, the rotor illustrated being of a form which may be used in the signals shown in Figs. 1, 4 and 6.

Similar parts may be designated by similar characters of reference throughout the views.

In Figs. 1 and 2 the numeral 10 indicates a suitable casing for containing the flexible shaft 12 and the rotor 11 and for holding the diaphragm 13; 14 is a resonator or amplifier secured to the casing in front of the diaphragm; and 15 is an incased electric motor secured to the casing 10 for driving the flexible shaft. This motor may be of suitable design, preferably like that used for the well known Klaxon warning signal and disclosed in my Patent No. 1,160,900 issued November 16th, 1915. The motor casing is preferably connected to the casing 10 by means of a screw-threaded neck 16 on the former which engages with an internally threaded boss 17 on the latter. A lock nut 18 is threaded on the neck 16 and serves to hold the parts in proper relation. The flexible shaft 12 here shown is in the nature of an elastic rod or wire. The rotor 11 is a

disk having a sleeve or hub 19 which is rigidly secured to the middle of the shaft, as by a driving fit, brazing or otherwise. The rotor is thus rigidly connected to a length of the flexible shaft, so as to hold this central length straight under all conditions, and parallel to the rigidly held end portions of the shaft now to be described. The bore in the sleeve 19 may be slightly flared at the ends, if desired, so as to eliminate the possibility of cutting of the shaft due to bending of the latter. The end lengths of the shaft are rigidly held by cylindrical bearings so as to be at all times in alignment. The upper bearing consists of a cylindrical journal 20 having a bore in which the end length of the shaft is rigidly secured, and a cylindrical bearing proper 21, which is preferably in the nature of a cap threaded into an opening in the top of the casing 10. The diaphragm 13 carries an anvil 27, which is preferably substantially V-shaped as shown in Fig. 3. The teeth 28 of the rotor in this form of the invention are preferably of wide V-shape.

The shaft 12 is directly connected to the armature shaft 26, so that, in this instance, the armature shaft constitutes the cylindrical journal for the lower end of the flexible shaft, and the unyielding cylindrical bearing 95 is the bearing in the neck 16. Thus, there is had a flexible shaft and a rigid shaft secured together end to end, the former carrying the rotor, and the latter protectin the motor from bodily vibrations. In this form of signal 100 the neck 16 may be screwed upward into the casing 10 until the top journal 20 just bottoms in the bearing cap 21, when the lock nut 18 can be set so as to hold the shaft in such manner that it normally has no flexure. The rotor 11 is preferably provided with teeth 28 of the form shown in Fig. 3, and the anvil 27 is preferably correspondingly formed as shown in that view, so that the action of the teeth is to produce a relative 110 movement between the shaft and the diaphragm in a direction that is normal to the diaphragm. In this form of signal the flexible shaft 12 is preferably comparatively 115 long and the rotor 11 is preferably comparatively heavy, so that the factor of elasticity is reduced and the inertia increased. The diaphragm 13 is preferably considerably larger than in Fig. 1 so as to have greater flexibility but is still stiffer than the shaft 12. In 120 this form of signal, the shaft 12 and the rotor 11 are revolved at a speed which is high as compared with the natural rate of vibration of the shaft and rotor. Thus, when the rotor is set in motion the shaft is cammed 125 away from the diaphragm by the reaction due to the teeth 28 riding over the anvil, and at the outset there may be a definite hammering action; but this may be regarded as ceasing or growing slight as the speed in- 130

creases and the shaft acquires a bowed or set position, which persists as long as the rotation at maximum speed continues, the reason being that the speed is so high that the 5 shaft has not sufficient time to snap back to produce the typical hammering or tapping action. The shaft 12 at the maximum speed may be regarded as yielding very slightly if at all under the successive contacts of the 10 teeth with the anvil, the teeth acting largely or mainly to cam the diaphragm repeatedly outward. In this way the flexible shaft is self-adjusting to a position where the rotor acts substantially as a driver of the dia- 15 phragm, or where the driving is in greater or less degree mutual.

In the form of signal shown in Fig. 4 the cylindrical journal 22 at the lower end of the flexible shaft 12 forms part of, or is rigidly secured to, a gear 24^a which meshes with a pinion 25^a on the upper end of the armature shaft 26. The pinion 25^a and the gear 24^a constitute a reducing gearing. The rotor teeth and anvil in this form of signal are preferably of the form shown in Fig. 7. This view illustrates a case in which the camming of the diaphragm and shaft is mutual, so that each engagement of a tooth with the anvil is partly a blow and partly a 30 camming action.

In both of the forms of signal so far described the flexible shaft has been solidly held at its end portions in cylindrical journals turning in fixed cylindrical bearings, 35 and its middle length has been rigidly secured to a sleeve on the rotor. Under these conditions the shaft when running assumes the compound curvature illustrated in exaggerated form in Fig. 2, with its end lengths 40 straight and in alignment, its middle length straight and parallel with the end lengths, and a compound curve formed in each portion between the middle and end lengths. As already described, these connections at 45 the ends and middle of the shaft greatly increase its durability and wear-resisting powers, besides holding the parts in true relation, and enables the stiffness of the shaft to be increased without necessitating shortening of the shaft or increasing its weight.

In Fig. 5 I have illustrated a signal in which the flexible shaft 12^a is reduced to half length, the rotor 11^a being fixed to the upper end portion of the shaft. The lower 55 end portion of the shaft is solidly held in a cylindrical journal constituting the armature shaft 26, as in Fig. 1. The rotor 11^a is held in true relation to the anvil 27^a during its vibratory movements by means of a yoke 30 having bearings which encircle the shaft, 60 preferably immediately above and below the rotor, and being pivotally supported, as on bracket lugs 31 projecting from the interior walls of the casing 10. The upper end 65 length 12^b of the shaft, may be rigid, con-

stituting in effect a rigid cylindrical journal, to which the flexible shaft 12^a is connected by a socket 12^c in which the upper end of the flexible shaft 12^a is rigidly received. The flexible shaft 12^a may or may not have 70 inherent elasticity. I have illustrated it as being without inherent elasticity, being the special form of universally flexible shaft formed from a spiral. In either event I may provide a spring 32 connected to the 75 shaft, for normally drawing the shaft toward the diaphragm. This spring is shown for purposes of illustration as being secured at one end to the yoke 30 and at the other end to a bracket 33 projecting from the 80 lower bracket lug 31. If the shaft 12^a possesses inherent elasticity this spring may serve to compensate for the omission for the upper half of the shaft. If the shaft is 85 flexible without possessing elasticity, then the spring supplies the necessary elasticity to cause the shaft to vibrate.

Figs. 6 and 7 show a similar construction to the last except that the rotor shaft is rendered flexible by universal joints 34. 26 is 90 an armature shaft as before, to which may be secured the axial lower section 12^d of the rotor shaft, of which the middle section 12^e is free to oscillate and the upper section 12^f is held in parallelism with the lower section 95 12^d by reason of the pivoted yoke 30. In this case also the spring 32 supplies the elasticity whereby the rotor flies back against the anvil to deliver a blow after each reaction-produced movement away from the diaphragm. In both this and the preceding case the spring 32 is less elastic than the diaphragm, so that the rotor has more tendency to yield under the camming action than 100 the diaphragm.

In the several forms of the invention a cylindrical journal or rigidly held portion at the lower end of the flexible rotor shaft enables the shaft and rotor to be driven successfully by the electric motor, since the armature and commutator of the latter are insulated from the bodily vibrations of the flexible shaft and rotor.

Having thus described my invention, what I claim as new, and desire to secure by Letters Patent, is:

1. A signal, comprising a diaphragm, a rotor adapted to set up diaphragm-vibrations, a flexible shaft carrying the rotor, being adapted for resilient lateral movement toward and from the diaphragm and having an unyielding cylindrical bearing, means for maintaining a length of the shaft including the region encircled by the rotor in parallelism with said bearing, and power means for driving said shaft.

2. A signal, comprising a diaphragm, a rotor adapted to set up diaphragm-vibrations, a flexible shaft carrying the rotor and adapted for resilient lateral movement to-

- ward and from the diaphragm, said rotor being formed or provided with a plurality of actuator elements approximately equidistant radially from the axis of rotation of 5 said shaft, a rigid cylindrical journal rigidly receiving and holding a length of said shaft, an unyielding cylindrical bearing receiving said journal, and a motor having driving connection with said shaft.
- 10 3. A signal, comprising a diaphragm; a rotor adapted to set up diaphragm-vibrations, a flexible shaft carrying the rotor and adapted for resilient lateral movement toward and from the diaphragm, rigid cylindrical journals of greater diameter than said shaft rigidly receiving and holding lengths of said shaft, the rotor being mounted intermediate said journals, unyielding cylindrical bearings receiving said journals, and a motor having driving connection with said shaft.
- 15 4. A signal, comprising a diaphragm, a shaft consisting of an elastic rod free to flex toward and from said diaphragm, rigid journals of greater diameter than said rod rigidly receiving and holding lengths of said shaft in alinement, a rotor adapted to set up diaphragm-vibrations carried by said shaft intermediate said journals, unyielding bearings receiving said journals, and power means for driving said shaft.
- 20 5. A signal, comprising a diaphragm, a rotor adapted to set up diaphragm-vibrations, a shaft carrying the rotor, consisting of an elastic rod free to flex with reference to the diaphragm, a solid cylindrical journal of greater diameter than said rod rigidly receiving a length of said shaft, and power means for driving the shaft, said rod and 25 rotor being approximately balanced.
- 25 6. A signal, comprising a diaphragm, a rotatable shaft flexible throughout and free to flex with reference to the diaphragm, bearings holding the end lengths of said shaft in alinement and against flexure, a rotor for setting up diaphragm-vibrations carried by an intermediate part of said shaft, and power means for driving said shaft.
- 30 7. A signal, comprising a diaphragm, a shaft flexible throughout its body and free to flex with reference to the diaphragm, bearings holding the end lengths of said shaft in alinement and against flexure, a 35 rotor for setting up diaphragm-vibrations, being fixed to said shaft and having means for maintaining an intermediate length thereof against flexure and in parallelism with the end lengths, and a motor having driving connection with said shaft at one of its solidly held end lengths.
- 40 8. A signal comprising a diaphragm, a comparatively heavy rotor free to move toward and from said diaphragm and provided with a plurality of spaced projections 45 for setting up bodily vibration of the center portion of said diaphragm, high speed power means and means for supporting said rotor and transmitting power thereto, the mass of the rotor and the relative resiliencies of said diaphragm and said means being such that said rotor will occupy a position adjacent to said diaphragm when the parts are at rest in normal position and will occupy a second and substantially definite position more remote from the diaphragm when said power means is in operation, due to the repulsive reaction between the diaphragm and rotor. 70
- 45 9. A signal, comprising a diaphragm, a flexible shaft free to vibrate with reference to the diaphragm, a rotor fixed to said shaft and formed or provided with a plurality of spaced teeth or projections for setting up diaphragm vibrations, a motor for driving the shaft and means for holding portions of the shaft against flexure and causing another portion to assume a compound curvature with said rotor in a position more remote from the diaphragm, due to repulsive reaction between the diaphragm and rotor. 75
- 50 10. A signal, comprising a diaphragm, a flexible shaft free to vibrate with reference to the diaphragm, a comparatively heavy rotor fixed to said shaft and formed or provided with a plurality of spaced teeth or projections for setting up diaphragm vibrations, and power means for driving the shaft at high speed, said shaft and rotor being of such flexibility and inertia as to acquire a continuous curvature with said rotor in a position more remote from the diaphragm due to repulsive reaction between the diaphragm and rotor. 80
- 55 11. A signal, comprising a diaphragm, a flexible shaft adapted for resilient lateral movement toward and from the diaphragm, a rotor adapted to set up diaphragm-vibrations carried by an intermediate portion of the shaft, rigid cylindrical journals secured to the ends of said shaft, an unyielding cylindrical bearing receiving one of said journals and having an end-thrust surface, said bearing being longitudinally adjustable, an unyielding cylindrical bearing for the other journal, and means for adjusting said other journal longitudinally in its bearing and locking it in adjusted position against axial movement. 85
- 60 12. A signal comprising a flexible diaphragm, a flexible shaft supported at both ends, a comparatively heavy rotor fixed to said shaft and formed or provided with a plurality of spaced teeth or projections for setting up diaphragm vibrations and power means for driving the shaft at high speed, said shaft and rotor being of such flexibility and inertia in respect to the flexibility and natural period of bodily vibration of said diaphragm as to cause said shaft to assume a continuous curvature with the axis of said 90
- 65 130

rotor, substantially stationary in a position
more remote from the diaphragm than the
axis of the terminal portions of the shaft,
due to repulsive reaction between the dia-
5 phragm and rotor.
